DESIGN FOR A BOX COVER

Martha H. Connor, Baltimore, Md., assignor to Owens-Illinois Can Company, Wilmington,
Del., a corporation of Delaware

Application February 12, 1937, Serial No. 67,620

Term of patent 7 years

To all whom it may concern:

Be it known that I, Martha H. Connor, a citizen of the United States, residing at Baltimore, in the State of Maryland, have invented a new, original, and ornamental Design for a Box Cover, of which the following is a specification, reference being had to the accompanying drawing, forming a part thereof.

In the drawing:

Fig. 1 is a plan view of a box cover showing my new design, the unornamented portions of the several areas involving a mere repetition of the completed portions of the ornamentation shown.

Fig. 2 is a side elevational view thereof.

I claim:

The ornamental design for a box cover substantially as shown and described.

MARTHA H. CONNOR.
